(No Model.)

C. F. BECK.
ELECTRIC LIGHT.

No. 322,033.

Patented July 14, 1885.

UNITED STATES PATENT OFFICE.

CHARLES F. BECK, OF PARIS, FRANCE, ASSIGNOR TO THOMAS S.
HARRISON, OF PHILADELPHIA, PENNSYLVANIA.

ELECTRIC LIGHT.

SPECIFICATION forming part of Letters Patent No. 322,033, dated July 14, 1885.

Application filed September 10, 1884. (No model.)

To all whom it may concern:

Be it known that I, CHARLES FREDERICK BECK, of Paris, in the Republic of France, have invented certain new and useful Improvements in Electric Lamps.

The following is a specification of my improvements, reference being had to the accompanying drawings, wherein—

Figure 1 represents a side view of the lamp proper and a vertical section through the inclosing globe of the same. Fig. 2 is a view at right angles to the position shown in Fig. 1. Figs. 3 and 4 are sectional views showing the position merely of the several parts at the lines $z z$ and $y y$, respectively. Fig. 5 is a plan view of the under side of the cap or cover of the lamp, showing certain of the parts in horizontal section, and Fig. 6 is a detail view of spring M.

In the drawings, A is a glass globe inclosing the apparatus, and attached by means of hooks $i i$ to the cap or cover B, from which the various parts of the lamp proper are suspended, and which in turn is provided with an attachment, C, for securing the whole in position, said attachment C being preferably tubular in form to conceal the conducting-wires $a a'$.

An inclined strip, L, preferably of vulcanite, is attached at the upper end of the cap C, said strip having a groove, t, upon one of its sides, being provided upon the other with a band of copper, E, extending along its entire length. Said band of copper is connected with the binding-post R, which forms an attachment for the connecting-wire a' .

At the bottom of the strip E is a metallic spring, M, of sufficient size to afford a good conductor for the current, and at the bottom of said spring is a finger, H, preferably of copper tipped with platinum, e, said copper finger H being rendered easily adjustable vertically in a slot, m, in the spring M by means of the set-screw m' . Pulleys $n n$ are arranged on each side of the vulcanite strip L, at or near its upper end, and similar pulleys, d d, on each side near its lower end.

A pencil of carbon, F, lies in the grooves of the strip L, and is provided at its upper

end with a cap, s, to which cords $p p$ are attached, the said cords passing down under the pulleys $d d$, then up and over the pulley n' , and being both fastened to a weight, b. A bridle, o, having a friction-roller, e, is arranged at the bottom of the strip L, so as to prevent the displacement of the carbon pencil F from the groove t, but to permit its free descent under the influence of the weight b. The spring M presses the finger H against the carbon pencil F, so as to afford a good electric contact between them. The tip of the pencil F rests upon the end of a thin curved arm, N, preferably of copper tipped with platinum j, said arm being attached by means of a hinge or pivot, k, to the base u of the binding-screw P, affixed to the under side of the cap or cover B, opposite to the point of attachment of the vulcanite strip L. To this binding-screw P the other wire, a, of the electrical circuit is attached.

Intermediate between the vulcanite strip L and the metal arm N is a vertical holding-piece, D, attached at its upper end to the under side of the cap B, and provided at its lower end with a jaw and set-screw, g, to clamp and hold a thin porcelain plate, G, the lower end of which is in contact with the platinum tip j at a point immediately alongside of the point of contact of the carbon pencil F therewith.

To place the parts in position, (the glass globe A being detached,) the arm N is swung outward upon its pivot k. The carbon pencil F is then run into the groove t of the vulcanite strip L from the bottom, and, when inserted, the cap s (which is arranged to spring over the end of the carbon) is attached thereto. The cords p are then connected with the eye of the cap s, and passed over the respective pulleys $d d$ and $n n$ on each side of the strip L, and made fast to the weight b. The arm N is then swung into position so that the tip of the carbon pencil F shall rest thereon, as shown in Fig. 1. The plate, G, of porcelain, is inserted in the jaw of the holder D, and secured by the screw g in such position that the end shall touch the tip of the carbon pencil F and shall rest upon the platinum end j of the arm N. Connection

being properly made by means of the binding posts R and P with the wires a and a', respectively, the current from a dynamo or other source of electricity is turned onto said wires, 5 (of which a' should be connected with the positive and a with the negative pole,) and the circuit is established through the copper strip E at the back of the vulcanite L, the spring M, the finger H and its platinum tip e, the end of 10 the carbon pencil F, the platinum tip j, and the arm N. By reference to Fig. 1, it will be seen that the small portion of the carbon pencil F through which the current passes is in contact laterally with the plate G of porcelain; but said 15 plate forms at this time no part of the circuit, the material being, when cold, a non-conductor. The passage of the current, however, heats the carbon tip, and by contact therewith the porcelain plate G, which, at a high temperature, 20 becomes measurably a conductor, and as soon as the tip of the pencil F is dissipated or wastes away by the action of the current, so that it no longer touches the platinum j, the circuit establishes itself through a portion 25 of the now heated porcelain plate G, which, by the resistance that it affords to the passage of the current, becomes highly incandescent. The pressure of the spring M against the carbon pencil F holds it in contact with the side 30 of the plate G with sufficient force to prevent its slipping entirely down so as to again rest upon the platinum j; but at the same time the weight b tends to press the carbon pencil downward, and hence to prevent it from getting 35 out of contact with the porcelain by reason of the continued wasting away of the carbon, should such action take place. It is therefore necessary that there should be a certain balance between the pressure of the 40 spring M and the weight b, since it is desirable to maintain the contact between the carbon pencil and the porcelain plate at a practically constant point. The distance of this point from the platinum tip j of the arm N is 45 determined by the actual size of the respective parts and the strength of the current; but I have obtained good results by the separation of a millimeter, thus causing the current to pass through the porcelain to that extent. 50 The adjustability of the finger H in the spring M facilitates the arrangement of the contact and determines the extent of carbon through which it is expedient to maintain the current.

I prefer to use porcelain as the interposed 55 material to be rendered incandescent, since I have found that it becomes very slightly pasty under the temperature attained, and hence affords a good contact for the end of the carbon pencil, and prevents the latter from slipping 60 down; but magnesia and various other refrac-

tory oxides and earths compressed into a hard plate may be substituted therefor. The qualities which I consider most important for the classification of such substitutes are as follows: The material should be sufficiently refractory 65 to retain its general shape under the temperature attained; it should not be friable or disposed to spall off in use, and it should be, when raised to the temperature which the proximity of the heated carbon affords, a conductor of such resistance as to become incandescent under the passage of the current.

The mechanical devices above described may be varied without substantial departure from the principle of my invention. Thus, instead 75 of depressing the carbon by means of a weight and maintaining it against the porcelain surface by means of a spring, other equivalent devices may be employed for the purpose, and hence, while I deem the apparatus above described a convenient embodiment of my invention, I do not desire to limit my claim to that exact method of construction.

Having thus described my invention, what I claim as new, and desire to secure by Letters 85 Patent, is—

1. In an incandescent electric lamp, the combination of a permanent electrode, a carbon electrode arranged to rest thereon, a plate of porcelain or other equivalent material arranged in contact with said electrodes, and means whereby, after the establishment of a current sufficient to develop the conducting-power of said plate by heat, the said carbon electrode is maintained in contact with said 90 plate at a substantially constant distance from said permanent electrode, the whole operating in the manner set forth.

2. In an electric lamp operating by the incandescence of a piece of porcelain or equivalent material, the combination of a holder for 100 said piece, a permanent electrode, a carbon-holder, and a pressure device for said holder against said piece at a substantially constant distance from said permanent electrode, the 105 whole operating substantially as set forth.

3. The combination of the swinging arm N, the holder D, having a clamping device at its lower end, the inclined strip L, having a way or groove on its edge for retaining the carbon, 110 the adjustable finger H, and suitable devices for pressing said finger laterally against the carbon and depressing the carbon longitudinally, substantially as and for the purposes set forth.

CH. F. BECK.
